12 Claims. (Cl. 177—353)

1

This invention relates to a device for periodically opening and closing an electric circuit.

An object of the invention is to provide such a device the periodicity of which is independent of fluctuations of the supply.

According to the invention a device for periodically opening and closing an electric circuit comprises a polarised relay having two opposed windings, means for passing current through one winding, means for passing the charging current of a condenser through the other winding, contacts controlled directly or indirectly by the relay to change the direction of current through the one winding and to start the discharge of a condenser through the other winding, and contacts controlled directly or indirectly by the relay for opening and closing said circuit.

Preferably adjustable resistances are provided associated with the relay windings for adjusting the period of a complete make and break of the circuit being controlled and the ratio between make and break.

The invention also comprises the use of a device as set out above in selective apparatus adapted to respond to signals consisting of a sequence of marks and intervening spaces of prescribed duration. One of such devices supplies impulses to a relay counting chain for measuring the duration of the marks, another supplies impulses to a second relay counting chain for measuring the duration of said spaces. Means controlled by the relay counting chains returns the apparatus to zero upon the occurrence of a mark or space of other than prescribed duration, and means controlled by the relay counting chains closes a circuit upon the occurrence of the correct sequence of marks and spaces.

The invention will be better understood from the following description taken in conjunction with the accompanying drawings, in which:

Fig. 1 shows a circuit and the parts connected therein which form the device according to the invention;

Fig. 2 shows curves for explaining the operation of Fig. 1;

Figs. 3A and 3B taken together show the circuit of a radio distress signal receiver, responding to a distress signal to give an alarm but not so responding to other signals;

Fig. 4 is a timing diagram for certain relays of Fig. 3.

Referring to Fig. 1 of the drawings, the circuit shown is adapted to remain in the condition shown until a relay ST is operated. Relay P is a polarized relay with two windings. Current

2

is normally flowing from battery B through a potentiometer PR to ground. Current also flows from a point on the potentiometer, through winding 1 of relay P, back contacts pp1, back contacts st1, ground. This current is adjusted to be sufficient to keep the armature of relay P against its spacing contact S, in which position relay PP is de-energised. Contacts st2 back, keep a condenser C short circuited through a resistance R6.

When it is desired to start the periodic operation of relay P, relay contacts st1 change over and contacts st2 open, due to operation of relay ST. Current then flows from battery B through resistance R4, front contacts st1, back contacts pp1, winding 1 of relay P, point on potentiometer PR, ground. This current tends to move the armature of relay P to its marking contact, but the effect is opposed by that of a charging current for condenser C flowing through resistances R4 and R3, winding 2 of relay P.

Curve A in Fig. 2 shows the variation of the current in winding 1 with time, and curve B the variation of current in winding 2 with time. The line c1c1 represents the current necessary to operate the armature of relay P to its marking contact. As the currents in the two windings are opposed, this operation of the armature does not take place until time t1 when the difference has become equal to c1c1.

When relay P closes its marking contact M, relay PP is operated and contacts pp1 change over. The current in winding 1 of relay P changes direction, flowing now from a point on potentiometer PR through winding 1 of relay P, contacts pp1 to ground. This current tends to move the armature of relay P to its spacing contact. The condenser C commences to discharge through winding 2 of relay P and the discharge current opposes the current in winding 1. The armature of relay P is thus not operated to its spacing contact until time t2.

Any variation of voltage of battery B will affect the current in each winding in the same manner, either on operation of marking or spacing contacts, so that such variation does not affect either the overall period of operation of relay P nor the ratio between the periods of closure of marking and spacing contacts.

Contacts of relay PP (not shown) may be used to open and close a circuit.

The point at which winding 1 of relay P is connected to potentiometer PR, and the values of resistances R3, R4 and the capacity of condenser C may be altered in order to alter the

overall period of relay P and the ratio between the periods of opening and closing of a circuit by contacts of relay PP.

The device above described may be used to produce makes and breaks of an electric circuit (impulses) for any purpose for which exact timing is important. In particular it is shown in Figures 3A and 3B as applied to a radio distress signal receiver. A marine distress signal consists of a series of three dashes each of four seconds in length separated by spaces of one second duration. A certain tolerance in the length of dashes and spaces is allowed in distress signal receivers and a dash is accepted as of correct length if between 3.5 seconds and 4.5 seconds duration, whilst a space is accepted as correct if it exceeds $\frac{1}{2}$ second approximately and does not exceed $1\frac{1}{2}$ seconds.

In the circuit shown in Figures 3A and 3B, relays P and PA are used, the circuits of which give an impulse time (make or break) of approximately 580 milliseconds with makes and breaks equal. The following four batteries shown by the conventional symbols of thick and thin lines are 120 volts; in Figure 3A the battery attached between ground and the terminal ST2, in Figure 3B the one attached between the resistor R₁ and ground, in the same figure the one attached between R₅ and ground, and in the same figure the one attached between the terminal PF2 and ground. These are used to feed the circuits of the polarized relays P and PA. The other batteries also shown by the same conventional symbols of thick and thin lines are 24 volts.

The terminal marked RC is connected to a relay in the output circuit of a radio receiver in such manner that when a relay in the latter circuit responds to a dash battery is applied to terminal RC to operate relays R and HR whilst during a space the battery is removed. On receipt of a correct distress signal, the circuit shown applies ground to terminal AA to operate an audible alarm.

The circuit is not in use until a locking key KS1 is operated.

The key KS1 prepares a circuit for a start relay ST. When a dash is received and battery is applied to terminal RC a circuit is completed for relays R and HR over ta1 back, sa1 back, tb1 back, sb1 back, tc1 back, sc1 back, st4 back, ground. Relay HR is a high speed relay and closes a locking circuit of R and HR to ground over hr1. R is a slow operating relay, having one winding shunted by its own back contacts. These relays are so arranged that relay HR releases within 1 millisecond if battery is removed from terminal RC, whilst relay R being slow to operate is not energised due to accidental signals. Relay R when energised removes the short circuit from its second winding and becomes fast to release.

At contacts r2 a circuit is closed for relay ST from battery, r2 front, winding of ST, n2 back and L1 back in parallel, key KS1, ground. When ST operates, contacts st1 change over the circuit for winding 1 of relay P, contacts st2 remove a short circuit from condenser C1 in the circuit of winding 2 of relay P, contacts st3 prepare a circuit for counting relays TA, etc., and contacts st4 open the circuit of R and HR which, however, remains closed at hr1 front until the signal comes to an end.

The circuit of relay P is like that of relay P in Fig. 1. Current flows from the 120 volt battery over resistances R₁ and R₂ to ground on

key KS1. Before relay SR operates current flows from a point between resistances R₁ and R₂ through winding 1 of relay P, pr1 back, st1 back, ground. When relay ST has operated, current flows from 120V battery, st1 front, pr1 back, winding 1 of relay P, resistance R₂, key KS1, ground. Charging current for condenser C1 flows over st1 front, pr1 back, resistance R₃, winding 2 of relay P, condenser C1, key KS1, ground. For production of impulses of the desired period, viz: 580 milliseconds with about 50% ratio relay P is a telegraph relay of the kind described in British specification No. 491,893, condenser C1 is 10 microfarads, R₁ is 60,000 ohms, R₃ is 30,000 ohms, whilst R₂ is adjustable between 25,000 and 30,000 ohms.

After an interval relay P closes its marking contact and operates a helping relay PP which at contacts pp1 operates a second helping relay PR. At contacts pr1 the current in winding 1 of relay P is reversed and the condenser charging circuit broken. At contacts pp2 relay SA is operated from battery winding 2 of SA, ta2 back, pp2 front, st3 front, ground.

The counting relays SA, TA, SB, TB, SC, TC are operated and released by the closing and opening of contacts pp2, as determined by the closing and opening of the marking contact p1, in a sequence which is used to time the period of a dash. The circuit for these counting relays is dependent upon contacts st3 being closed; when these contacts open all the said counting relays are released. The sequence of operation of the counting relays can be seen from Fig. 4. Horizontal lines indicate the periods during which the respective relays are operated.

When relay P opens its marking contacts, relay PP releases followed by PR. During a very brief interval whilst back contacts pp4 are closed and before front contacts pr2 are opened a short circuit of condenser C1 exists to drain off any residual charge therefrom.

When relay PP releases, relay TA operates in series with winding 1 of relay SA, the circuit being completed over sa2 front, pp2 back. A non-inductive shunt around winding 2 of relay SA ensures that contacts sa2 remain closed during possible vibration of contacts pp2. SA remains operated. Relay TA completes, at contacts ta3 front a circuit for winding 1 of relay SB, which relay operates.

When relay PP again operates a circuit for relay TA is completed, independently of relay SA, over ta2 front and pp2 front and relay TA remains operated but relay SA releases. Relay SB remains operated.

When relay PP releases for the second time relay TA is released and relay TB is operated in series with winding 1 of relay SB. Relay SC operates over winding 2 and tb4 front.

When relay PP operates for the third time, relay SA again operates and the above described sequence of operation and release of relays SA and TA continues to occur in subsequent periods. The pairs of relays SB and TB and SC and TC operate and release similarly to relays SA and TA, their cycles of operation depending upon contacts of TA and TB respectively instead of upon contacts of PP.

It will be seen from Fig. 4 that the periods of operation and release of relays SA and TA are twice those of relay PP and in consequence the periods of operation and release of relays SB and TB are twice those of relay TA and the periods

of operation and release of SC and TC twice those of TA.

After relay PP has released after its sixth operation, i. e., after a period of approximately 3.5 seconds, relays SB, TB and TC are all operated and relay D operates over tc_3 front, sb_2 front, tb_2 front, st_3 front, ground, and locks over d_3 front, st_3 front to ground. Relay D prepares a circuit for relay PZ over ps_1 back, d_1 front, in series with ST, but remains short circuited whilst relay R is operated.

If the dash ceases after the termination of the sixth operation of PP (and before the end of a certain limiting period as explained hereafter), relay PZ operates in series with relay ST. Relay PZ closes a locking circuit for itself over ps_1 front, qa_1 back, ra_1 back and rb_1 front in parallel, keys KS, ground and breaks the circuit for ST which releases.

If the received dash lasts longer than the eighth period of operation of PP, i. e., longer than 4.5 seconds approximately, relay DD operates over d_2 front, tc_2 back, tb_2 back, st_3 front, ground and breaks the operating circuit for PZ. Relay DD locks over dd_2 front to st_3 front and ground. Thus whilst the dash continues further relay PZ cannot operate. If then the dash ceases after 4.5 seconds, relay ST releases, its circuit being broken at contacts r_2 and the whole of the circuits return to normal condition.

Relay PZ is the relay, the energisation of which indicates that a dash of correct duration has been received.

After the release of ST and the return to normal of the counting relays SA, etc., a circuit is again completed from ground over st_4 back, sc_1 back, tc_1 back, sb_1 back, tb_1 back, sa_1 back, ta_1 back for relays R and HR to respond to any further dash. Any short signals received, due to atmospherics, in the pause between dashes, are unlikely to operate relay ST.

The pause between dashes must now be measured and the end of the phase is signalled by the re-operation of relay ST and the end of a pause of correct duration by the re-operation of relay ST whilst relay PZ is still operated. The minimum period allowed for a correct pause is the period within which PZ operates, ST releases, the counting relays SA, TA, etc., release and relay ST re-operates completely. The maximum time allowed for a correct pause is 1.5 seconds approximately and is timed by the response of counting relays QA, RA, QB and RB, to impulses produced by relay PA the circuits of which are arranged in the same manner as those of relay P. Contacts ps_2 , on changing over change over the circuits of relay PA and contacts ps_5 prepare circuits for counting relays QA, RA, QB and RB.

After an interval relay PA closes its marking contacts pa_1 , and operates relay PT. Front contacts pt_2 complete a circuit for relay QA over winding 2. Relays QA, RA, QB and RB operate and release in the same manner and at the same intervals as relays SA, TA, SB and TB and their sequence of operations is shown in the lower part of Fig. 4. At the end of the third operation of relay PT, relays QA, RA and RB are all in operated condition and the circuit of PZ is broken at contacts qa_1 , ra_1 and rb_1 in parallel and PZ releases. Release of PZ stops the operation of relay PA and also releases the counting relays QA, RA, QB and RB so that the circuit is in the same condition as before the receipt of any signals.

When PZ first operated, a circuit was completed for relay L, battery, winding 2 of relay L, m_2 back ps_4 front ps_3 front, key KS, ground. Relay L prepares a circuit for relay M and when PZ releases, relay M operates in series with winding 1 of relay L, l_3 front, ps_4 back, st_2 front, key KS, ground. If relay PZ releases before ST operates, however, this circuit is not completed and relay L releases.

10 Relays L and M operated together therefore record the conclusion of a correct pause period immediately after the first correct dash period.

Relay ST restores the circuits of relay P and relay PP commences impulsive as before, the number of these impulses being counted by the counting relays SA etc. in the same manner as before. It should be noted that PZ is not immediately released upon the operation of relay ST, but that relays PA and PT go on impulsive and after these impulses PZ is released in time for its re-operation when required on a dash exceeding 3.5 seconds. Then in the same manner as above described relay PZ operates if the second dash period is of correct length. On this operation, a circuit is completed for relay M independently of relay L over m_2 front, ps_4 front, ps_3 front, KS, ground. Relay L releases. Relay N then operates over l_2 back, m_1 front, ps_3 front, KS, ground; and locks over n_3 front and the same circuit.

20 If relay PZ is prevented from operating because the dash lasts too long, the circuit for relays M and L in series over ps_4 back, and st_2 front is broken when ST releases at the end of the dash period and relays M and L are released. The operation of relay N is thus a record that a second dash of correct duration has been received.

When PZ operates relays PA and PT begin impulsive as before to time the pause period. If 40 ST re-operates before the pause has lasted long enough to release PZ the locking circuit for relay N goes over n_3 front, st_2 front, key KS, ground. If, however, the pause lasts too long, so that PZ is released before relay ST operates the locking 45 circuit of relay N is broken and that circuit releases.

The re-operation of ST starts relays P and PP impulsive to time the third dash. If this third dash is of correct length, PZ re-operates and relay L operates over m_2 back and its original circuit. A circuit is now closed for relay N over l_2 front, n_2 front, key KS, ground. Relay L is also held operated either over m_2 back, ps_4 front, or in series with M over l_3 front and ps_4 back, 55 n_3 front and the same locking circuit as relay N. Ground from key KS is extended over l_1 front, n_1 front to terminal AA to give an audible alarm.

The periods of pulsation of relays P and PA may be set to the correct value by adjustment of 60 resistances R2 R6. In order to provide for a check of the periods of these relays test keys KT1 and KT2 are provided. Key KT2 when operated causes the operation of relay R, followed by that of ST and the pulsing of relays P and PP. Key KT1 when operated causes the operation of relay PZ and the consequent pulsing of relays PA and PT. The impulses of contacts pp_3 or pt_3 operate a counting meter CM when key KT3 or KT4 is closed. The adjustment required is such that for relays P and PP the meter should be operated between 102 and 105 times a minute, whilst for relays PA and PT the meter should be operated between 120 and 124 times a 70 minute.

What is claimed is:

1. In an automatic signaling system, a polarized relay having an armature electromagnetically controlled by two opposite windings each establishing any one of two switching positions in accordance with current polarity, a first circuit means connected to one of said windings, means for supplying current to said first circuit means, a second circuit means connected to the second of said windings and comprising capacitance means, means for supplying current to said second circuit means to cause charging of said capacitance means, a first switching means controlled by said relay for reversing the direction of current in said first circuit means and for discharging said capacitance means in said second circuit means, and a second switching means controlled by said relay to open and close periodically in accordance with the charging and discharging of said capacitance means.

2. In an automatic signaling system, a polarized relay having an armature electromagnetically controlled by two opposite windings each establishing any one of two switching positions in accordance with current polarity, a first circuit means connected to one of said windings, means for supplying current to said first circuit means, a second circuit means connected to the second of said windings and comprising capacitance means, means for supplying current to said second circuit means to cause charging of said capacitance means, a first switching means controlled by said relay for reversing the direction of current in said first circuit means and for discharging said capacitance in said second circuit means, a second switching means controlled by said relay to open and close periodically in accordance with the charging and discharging of said capacitance means, and a third switching means for selectively maintaining said capacitance means in a steady state while maintaining a holding current through the winding not connected with said capacitance means.

3. In an automatic signaling system, a polarized relay having an armature electromagnetically controlled by two opposite windings each establishing any one of two switching positions in accordance with current polarity, a first circuit means connected to one of said windings, means for supplying current to said first circuit means, means for adjusting the current of said winding to vary operation and release times of said relay, a second circuit means connected to the second of said windings and comprising capacitance means, means for supplying current to said second circuit to cause charging of said capacitance means, a first switching means controlled by said relay for reversing the direction of current in said first circuit means and for discharging said capacitance means in said second circuit means, and a second switching means controlled by said relay to open and close periodically in accordance with the charging and discharging of said capacitance means.

4. In an automatic signaling system, a polarized relay having an armature electromagnetically controlled by two opposite windings each establishing any one of two switching positions in accordance with current polarity, a first circuit means connected to one of said windings, means for supplying current to said first circuit means, means comprising a potentiometer for adjusting the current of said winding to vary operation and release times of said relay, a second circuit means connected to the second of said windings and

comprising capacitance means, means for supplying current to said second circuit means to cause charging of said capacitance means, a first switching means controlled by said relay for reversing the direction of current in said first circuit means and for discharging said capacitance means in said second circuit means, and a second switching means controlled by said relay to open and close periodically in accordance with the charging and discharging of said capacitance means.

5. A system according to claim 1, comprising means for maintaining said capacitance means in a steady state and maintaining a holding current through the winding of the relay not connected to said capacitance means, to render the system inoperative.

6. A system according to claim 4, in which said one winding is connected to a point on said potentiometer whereby the current in said winding is adjustable to vary at least one of the following characteristics: the ratio between the time of operation and release of said polarized relay, and the complete period of operation and release.

7. A system according to claim 1, comprising means for operating said first and second circuit means in accordance with the duration of a signal received, a series of counting relays successively operated by a number of successive timing impulses produced by said second switching means for the duration of said signal, relay means for evaluating a signal of predetermined duration, and circuit means for energizing said relay means, including preparing contacts and operating contacts, said preparing contacts being operated by a counting relay corresponding to the passage of a predetermined number of timing impulses, and said operating contacts being operated by the ceasing of the signal producing said timing impulses.

8. A system according to claim 1, comprising means for operating said first and second circuit means in accordance with the duration of a signal received, a series of counting relays successively operated by a number of successive timing impulses produced by said second switching means for the duration of said signal, relay means for evaluating a signal of predetermined duration, circuit means for operating said relay means, including preparing contacts and operating contacts, said preparing contacts being operated by a counting relay corresponding to the passage of a predetermined number of timing impulses, and said operating contacts being operated by the ceasing of the signal producing said timing impulses.

45 9. A system according to claim 1, comprising means for operating said first and second circuit means in accordance with the duration of a signal received, a series of counting relays successively operated by a number of successive timing impulses produced by said second switching means for the duration of said signal, relay means for evaluating a signal of predetermined duration, circuit means for operating said relay means, including preparing contacts and operating contacts, said preparing contacts being operated by a counting relay corresponding to the passage of a predetermined number of timing impulses, and said operating contacts being operated by the ceasing of the signal producing said timing impulses, and further relay means operated by a counting relay after the passage of a predetermined number of timing impulses greater than the foregoing one, and for restoring the polarized relay into the same state as before the reception of a signal.

60 10. A system according to claim 1, comprising means for operating said first and second circuit means in accordance with the duration of a signal received, a series of counting relays successively operated by a number of successive timing impulses produced by said second switching means for the duration of said signal, relay means for evaluating a signal varying in duration between predetermined limits, further circuit means for operating said relay means, said further circuit means including preparing contacts and operating contacts, said preparing contacts being operated by a counting relay corresponding to the passage of a predetermined number of timing

impulses, and said operating contacts being operated by the ceasing of the signal producing said timing impulses, and further relay means operated by a counting relay corresponding to the passage of a predetermined number of timing impulses greater than the foregoing one, for restoring the polarized relay into the same state as before the reception of the signal, the difference between the first and second numbers of timing impulses being two timing impulses and equal to the tolerance permissible for the duration of a signal.

10. In an automatic signal system according to claim 1, comprising a second polarized relay having an armature electromagnetically controlled by two opposite windings and establishing any one of two switching positions in accordance with current polarity, relay means operating said second polarized relay and controlled by the second switching means of the first polarized relay in response to a normal duration dash signal controlling its first and second circuit means, said second polarized relay having first and second circuit means connected to its two windings, respectively, one of said circuit means comprising capacitance means, said circuit means being controlled by a pause received succeeding said normal duration dash, further switching means controlled by said second polarized relay to open and close periodically in accordance with the charging and discharging of the capacitance means of said second polarized relay, a series of counting relays successively operated by a number of successive timing pulses produced by said further switching means for the duration of said pause, relay means for evaluating a pause of predetermined duration, and further circuit means for energizing said relay means, said further circuit means including preparing contacts and operating contacts, said preparing contacts being operated by a counting relay corresponding to the passage of a predetermined number of timing impulses, and said operating contacts being operated by the ceasing of the pause producing said timing impulses.

11. In an automatic signal system according to claim 1, comprising a second polarized relay having an armature electromagnetically controlled by two opposite windings and establishing any one of two switching positions in accordance with current polarity, relay means operating said second polarized relay and controlled by the second switching means of the first polarized relay in response to a normal duration dash signal controlling its first and second circuit means, said second polarized relay having first and second circuit means connected to its two windings, respectively, one of said circuit means comprising

ing capacitance means, said circuit means being controlled by a pause received succeeding said normal duration dash, further switching means controlled by said second polarized relay to open and close periodically in accordance with the charging and discharging of the capacitance means of said second polarized relay, a series of counting relays successively operated by a number of successive timing pulses produced by said further switching means for the duration of said pause, relay means for evaluating a pause of predetermined duration, further circuit means for operating said relay means, said further circuit means including preparing contacts and operating contacts, said preparing contacts being operated by a counting relay corresponding to the passage of a predetermined number of timing impulses, and said operating contacts being operated by the ceasing of the pause producing said timing impulses, and further relay means operated by a counting relay after the passage of a predetermined number of timing impulses greater than the foregoing one, and for restoring the polarized relay into the same state as before the reception of a signal.

12. In an automatic signal system according to claim 1, comprising a second polarized relay having an armature electromagnetically controlled by two opposite windings and establishing any one of two switching positions in accordance with current polarity, first relay means operating said second polarized relay and controlled by the second switching means of the first polarized relay in response to a normal duration dash signal controlling its first and second circuit means, said second polarized relay having first and second circuit means connected to its two windings, respectively, one of said circuit means comprising capacitance means, said circuit means being controlled by a pause received succeeding said normal duration dash, further switching means controlled by said second polarized relay to open and close periodically in accordance with the charging and discharging of the capacitance means of said second polarized relay, second relay means controlled by said further switching means in response to a normal duration pause, said first and second relay means including counting relays for registering the number of succeeding dashes and dots of correct duration, and alarm means controlled by at least one of said counting relays in response to the registration of a predetermined number of correct dashes separated by correct dots.
